(57) **CLAIM**

The ornamental design for a bottle, as shown and described.

DESCRIPTION

FIG. 1 is an upper perspective view of a bottle embodying my new design;

FIG. 2 is a front elevational view thereof, the left side elevational view, the right side elevational view and the rear elevational view being identical to the front elevational view;

FIG. 3 is a top plan view thereof; and,

FIG. 4 is a bottom plan view thereof.

The dotted line representations of a bottle opening and threads in FIGS. 1-3 and bottom surface contours in FIG. 4 are for illustrative purposes only and form no part of the claimed design.
